Patented Sept. 7, 1915.

UNITED STATES PATENT OFFICE.

HENRY E. SOUTHWORTH, OF BURLINGTON, VERMONT, ASSIGNOR TO PORTER SCREEN COMPANY, OF BURLINGTON, VERMONT.

WINDOW-SCREEN.

1,153,140.

Specification of Letters Patent.

Patented Sept. 7, 1915.

Application filed April 21, 1915. Serial No. 22,924.

To all whom it may concern:

Be it known that I, HENRY E. SOUTHWORTH, a citizen of the United States, and a resident of Burlington, in the county of Chittenden and State of Vermont, have invented a new and useful Improvement in Window-Screens, of which the following is a specification.

This invention is directed to that class of extensible screens in which the clips, or connecting slides, that hold the screen sections together while permitting them to slide upon one another within limits, are located in the meeting faces of the overlapping rails of the screen sections so as to be practically concealed from view.

The invention resides more particularly in the clip or connecting slide, the characteristic of which is that when once inserted into place in the rail, or other body, in which it is to be seated, it is thereupon and thereby automatically locked and held permanently in that position, incapable of further movement in any direction with reference to the said rail. This feature I believe to be new with me beyond its preferred structural embodiment hereinafter described.

The advantages of the invention are material. It permits the sections which are to be united to be finished and made complete before being assembled together, and it does away completely with the use of nails or other extraneous means for fastening the clip or slide to its section, not only effecting an economy in labor as well as material, but also avoiding the damage to the screen rail which frequently is occasioned by the nailing operation.

In the accompanying drawings, to which reference will now be made for a better understanding of the invention—Figure 1 is a perspective view of a clip, or connecting slide, embodying my invention in its preferred form. Fig. 2 is a view of a two part sectional screen, having its sections connected by said clips—portions of the screen being broken away. Fig. 3 is a section partly in elevation on line 3—3, Fig. 2. Fig. 4 is a plan of the clip, with A' shown in dotted lines.

The screen, except as to the clips, may be of any usual or suitable construction, it being composed, in the present instance, of two overlapping screen sections consisting each of top and bottom rails A, a stile or

outer vertical end rail B, and an inner or center iron C, together with wire cloth or netting D secured thereto. The clips which hold the screen sections together are located, as usual in this class of screens, in the ends 60 A' of the rails which extend inwardly beyond the center irons C.

The clip itself, which in this instance is made of wire—a single length of wire—is bent and fashioned as shown in Fig. 1 to provide essentially three parts; a runner head or slide proper a, adapted to fit and run in the groove in the rail of the opposite section; a base b which is to be seated permanently in the groove in its own section; 70 and the neck c, connecting the two parts a and b. In the overlapping meeting faces of the top and bottom rails of each section are formed longitudinal undercut grooves d—one groove in each rail—of shape and size to accommodate the base b and head a of the slide—the said parts being so shaped that the same groove will receive either part indifferently. In each pair of meeting overlapping rails A the grooves d in their meeting faces match and register, so that the neck c of the clip can protrude through from one to the other, as shown.

To unite the clip with the rail A to which it is to be made fast, its base b is entered, 85 loop end foremost, into the groove d therein from the inner end of said rail, and it is pushed forward therein until a detent e at the outer extremity of the clip brings up against the rail and prevents further inward movement of the clip. The base of the clip is provided with a second detent, at a point nearer its front, consisting in this instance of the outwardly extending, spring yielding, spur end f of the looped front of the base b, 95 which bears outwardly against the side of the groove d and is spring yielding when the clip is pushed in, but at once acts as a detent to arrest movement in the other direction. Thus after the clip has once been 100 pushed home into its seat in the rail A, its further movement will be arrested automatically and permanently by the two detents e, f, the former preventing its further advance, and the latter its withdrawal, and 105 the clip being secured immovably to its rail without the employment of nails or other extraneous fastening means.

To assemble the screen sections, which before assembling are made complete except- 110

ing that the clips are yet to be applied, a clip is fitted by its head to each top and bottom section rail A, the clip being entered by its head into the groove *d* of that rail at 5 the inner end thereof, and then run back in the groove until it brings up against the stile B of that section—the clip being so entered that its outer end, that is to say the end where the detent *e* is located, will be 10 next to, and bring up against, the said stile B. There is thus associated with each section rail A a clip, held therein by its head loosely in the groove *d* in that rail, with its 15 detent end *e* outermost and next to the stile B of that section. The sections, thus preliminarily associated with the clips, are assembled by placing the one on the other—stile ends outermost and rails A overlapping one another—there being sufficient interval 20 left between the inner ends of the rails A of the one section and the stile B of the other section to accommodate the clips loosely associated with the latter section. This will bring the toes or front ends of the bases *b* 25 of the clips opposite to and in line with the open ends of the grooves *d* in the rails with which they are to be permanently associated; and then by simply shoving the screen sections together with endwise pressure, the bases *b* will be forced into their 30 grooves, as the sections slide together, until by the time the inner ends A' of the rails A of the one section have brought up against the stile B of the other section, the bases *b* 35 will have been forced home in their seats, and the outer detents *e* will have brought up against the rail ends to prevent further inward movement of the clips. Outward movement of the clips from this position is 40 prevented by the detents *f*, as before explained. And thus the clips, when once seated, are locked permanently in place automatically and without the employment of any extraneous fastening means whatever.

45 It is manifest that the construction of the clip may widely vary without departure from the principle of my invention. It need not be made of wire or in one piece; although I prefer that construction on the 50 score of efficiency, simplicity and cheapness. It can be made of sheet metal, with head, base and connecting neck of any suitable construction, whether made on one or more pieces. What is essential, and what I believe to be new with me, is the association

with what I have termed the base of the clip—that is to say the part which is to be fastened to its rail—of two automatically operating detents, the one permitting its entrance into the grooved rail, and its movement therein inwardly for a predetermined distance only, and the other permitting inward movement of the clip, but arresting outward or return movement, whereby the clip, having once entered the predetermined distance into the rail with which it is to be associated, is there automatically held in place against further movement in either direction.

What I claim therefore, and desire to secure by Letters Patent, is:

1. In an extension screen, a connecting slide or clip for connecting the overlapping rails of screen sections, having a base adapted to enter and move in the groove in the 75 rail with which it is to be associated, a detent associated with said base to permit said inward movement of the base for a predetermined distance only, and a second detent also associated with said base, which permits inward but arrests outward or return movement of the base, whereby said base, having once entered the predetermined distance into the rail with which it is to be associated, is there automatically held against 85 further movement in either direction, substantially as and for the purposes hereinbefore set forth.

2. In an extension screen, two screen sections, the overlapping rails of which have 90 in their meeting faces each a longitudinal horizontal undercut groove *d*, in combination with clips, one for each rail, having a base *b* seated in groove *d* in inner end A' of its section rail, and 95 a head which loosely enters and engages the groove *d* of the opposite rail, the base *b* having at its outer extremity a detent *e* which brings up against the end of its rail when the base has entered the groove there- 100 in a predetermined distance and thus prevents further inward movement of the same, and, at a point nearer its other end, an automatically acting, spring yielding, detent *f* which permits inward, but prevents out- 105 ward, movement of the base, substantially as and for the purposes hereinbefore set forth.

In testimony whereof I affix my signature.

HENRY E. SOUTHWORTH.
